UNITED STATES PATENT OFFICE.

THOMAS P. FOSTER, OF SEAL COVE, NEW BRUNSWICK, CANADA.

ANCHOR.

1,324,244.

Specification of Letters Patent.

Patented Dec. 9, 1919.

Application filed April 22, 1919. Serial No. 292,004.

To all whom it may concern:

Be it known that I, THOMAS P. FOSTER, a subject of the King of Great Britain, residing at Seal Cove, Province of New Brunswick, Canada, have invented certain new and useful Improvements in Anchors; and I do hereby declare that the following is a full, clear, and exact description of the invention, such as will enable others skilled 10 in the art to which it appertains to make and use the same.

The present invention relates to anchors, and an object of the present invention is to provide a device of this character with an 15 auxiliary coupling connection whereby a substantially direct pull may be gained whereby should the flukes of the anchor be fouled by rocks or other obstructions it can be easily and readily released, thereby preventing the anchor from becoming lost when being used.

With the above and other objects in view which will hereinafter appear as the description continues, the invention consists of 25 the novel features of construction, combination and formation of parts as will be hereinafter more fully described and particularly pointed out in the appended claim.

In the accompanying drawings has been 30 shown a simple and preferred form of the invention, it being, however, understood that no limitation is necessarily made to the precise structural details herein exhibited, but the right is hereby reserved to any 35 changes, alterations or modifications to which recourse may be had that come within the scope of the claim without departing from the spirit of the invention or sacrificing the efficiency of the same.

40 In the accompanying drawings:

Figure 1 is a side elevation of the anchor embodying the present invention;

Fig. 2 is an end elevation of the same;

Fig. 3 is a detail horizontal section taken 45 on the line 3-3 of Fig. 1; and,

Fig. 4 is an enlarged detail section taken on the line 4-4 of Fig. 3.

Referring now more particularly to the accompanying drawings wherein like and 50 corresponding parts are designated by simi-

lar reference characters throughout the several views.

The anchor embodying the present invention comprises the usual crown portion 1 having the flukes 2 formed with the opposite 55 ends thereof. A shank 3 is also preferably cast with the crown 1 and has secured within its upper end the usual stock 4. The shank 3 may be made somewhat lighter than the shanks used on ordinary anchors, due to 60 the fact that the cable is not connected directly to the shank, and this shank may be made so as to only have sufficient strength for righting the anchor. The anchor as so far described is substantially the same as 65 ordinary anchors and may be of any desired size. Formed with the upper face of the crown 1 are the ears 5, extending through each pair of ears 5 is a bolt 6 and these bolts 6 are retained in position by the cotter pins 70 or like fastening members 7. In the present anchor a second shank 8 is employed which is formed of a U-shaped bar having enlarged square lower ends 9 which are secured within the ears 5 by means of the bolts 75 6. This auxiliary shank 8 extends over and down along the opposite sides of the shank 3. Connected to this shank 8 is a ring 10 and the usual cable is secured to this ring.

When the anchor is dropped from a ship 80 upon the river bottom the flukes are likely to become fouled by roots, rocks or other obstructions in the river bottom, and if the cable was connected directly to the shank 3 it would be almost impossible to withdraw 85 the anchor and in most cases the anchors are lost. By providing the auxiliary shank 8 and having the ring 10 loosely mounted thereupon it is apparent that should any one of the flukes be fouled by obstructions in 90 the river bottom that the ring 10 would travel upon the auxiliary shank 8 until it has assumed a position whereby a substantially direct pull might be gained upon the anchor so as to withdraw the same from its 95 fouled obstruction. When the anchor flukes are released from the obstructions the anchor may again fall to one side and it will again take hold upon the crown when the strain is exerted upon the cable, due to 100

the fact that the ring 10 is permitted to readily slide upon this auxiliary shank 8.

Having thus fully described my invention, what I claim as new and desire to secure by Letters Patent is:

In an anchor of the character described, comprising a crown portion having flukes, ears and a shank formed integral therewith, an auxiliary shank formed of an inverted 10 U-shaped rod surrounding said shank and

having enlarged lower ends secured within the said ears, a ring connected to said rod and slidably mounted thereupon and a cable connected to said ring.

In witness whereof I have hereunto set 15 my hand.

THOMAS P. FOSTER.

Witness:

J. W. WOOSTER.
